DRESSING HOLDER FOR GRINDING
WHEELS

Hubert H. May, Hartford, Conn.

Application September 27, 1946, Serial No. 699,616

3 Claims. (Cl. 51—5)

1

This invention relates to an improved dressing and dressing holder for grinding wheels. While not limited thereto, it has particular application to a new and improved device for dressing grinding wheels at relatively short intervals so as to allow efficient use of the wheels for prolonged periods of time.

The new and improved device is particularly useful where a handy dressing device is desired as a readily available part of the grinding wheel installation. The device is therefore easy to install and readily operable and permits manipulation at maximum speed.

In accordance with one preferred form of the invention an abrasive dressing is adjustably held in position by means of a simple and efficient holder hugging the abrasive bar and preventing undue vibration due to the dressing action yet permitting ready adjustment when the dressing surface is worn down.

In accordance with another phase of this invention, a new pointed metal dressing device is attached to the same dressing holder permitting ready use in adjusting the dressing of the grinding wheel, and in roughing it up during, after and before the grinding operation.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective side view showing a grinding wheel with one preferred dressing device made in accordance with the instant invention in position as during the dressing operation.

Fig. 2 is a lengthwise central cross section of the dressing device illustrated in Fig. 1.

Fig. 3 is a perspective view of another embodiment of the instant invention showing a new and novel star shaped metal grinding tool in position.

Fig. 4 is a partial vertical section of the device of Fig. 3 taken on the line 4—4.

Fig. 5 is a perspective view of a further modification of the present invention.

Fig. 6 is a partial vertical sectional view taken on the line 6—6 of Fig. 5.

Fig. 7 is a perspective view of another preferred form of the invention using the abrasive dressing bar and the dressing tool in its disengaged position.

Fig. 8 is a vertical section through the holding 55

2

and the position-locking means taken on the line 8—8 of Fig. 7.

Fig. 9 is a vertical section through line 9—9 of Fig. 8.

Fig. 10 is a vertical section through line 10—10 of Fig. 8.

Fig. 11 is a perspective side view of the device of Figs. 7—10 taken from the side opposite to the one in Fig. 7 and showing the device in position for simultaneous operation of dressing stone and wheels.

Fig. 12 is a perspective view of the protective cover shown in Figs. 5 and 6.

In the preferred embodiment of the invention, 15 an abrasive dressing stone 11 is supported on a base 10 by a holder 12 hugging the stone and covering its lower side as well as the major part of two of the side portions. The base 10 may be secured in a clamp (not shown) fixed relative 20 to the grinding wheel. The dressing stone 11 is securely held by the abovementioned holder 12 and a clamping device 13 which may be tightened or adjusted by means of clamping screw 14 resting on washer 15 in turn resting on the clamping 25 device 13 which in turn engages a longitudinal slot 16 in the wall of said holder 12. The tip of the dressing stone 11 engages abrasive grinding wheel.

It will be readily seen from Figs. 1—2 and from 30 the above description that in operation the clamping screw 14 is first loosened and the clamping device 13 pushed in loose position toward the rear of the slot 16 permitting dressing stone 11 to be inserted between the sidewalls of the holder

35 12 and between the bottom wall of said holder 12 and the clamping device 13. Clamp 13 is now advanced pushing the dressing stone 11 toward the grinding wheel 17. When operative contact is made between grinding wheel 17 and dressing 40 stone 11, the clamping device 13 is adjusted by means of clamping screw 14 so as to permit tight positioning of dressing stone 11 within its confines.

In accordance with another phase of the 45 instant invention illustrated in Figs. 3 and 4 a metallic disc dressing tool 18 consisting of toothed star-shaped dressing discs 19 and round dressing discs 20 in alternating positions is held in secure operating condition on an axle 21 locked by means 50 of locking nut 22 in holding device 12. This holding device 12 is formed with a base 10 so that it may be supported in the aforementioned clamp, and a curved front portion 10^a which acts as a safety shield over the star-shaped dressing discs 19.

In the modification of the invention shown in Figs. 5 and 6 an adjustable non-breakable plastic protector 24 is secured to the top of holding device 12 when using it in this or similar connections so as to prevent accidents.

In the embodiment of the invention shown in Figs. 7-11 the device shown in Figs. 1-2 is held in position on holder 12 above sheet metal arms 25 which may be welded to the bottom of holder 12, extending at an angle from said holder 12 and carrying axle 21 locked in position by means of lock nut 22 while securing the abrading dressing discs 18.

While insertion of the dressing devices 11 and 18 is as simple with the new device as with the above described embodiment of the invention, the new device may readily be swivelled around central axle 26 so as to alternatively bring into operating position either abrasive dressing stone 11 as shown in Fig. 7 or abrasive dressing discs 18.

Various holding devices may be utilized to adjustably hold the device of Figs. 7-13, but I prefer the one illustrated in these views which utilizes tooth 28 fitting securely into spaced grooves 27 of positioning and holding arms 26 which may be attached to holding means for the wheel or be supported separately. One of the two cooperating holding arms 26 harbors a compression spring 30 resting upon vertical inside wall 31 and urging a hollow head 29 towards the side wall of support 12.

When adjusting the position the holding device 12 is pressed so as to compress spring 30, tooth 28 is placed in front of any desired cooperating groove 27 and the device is then released securely locking it in place.

The head 29 carries a trunnion 29^a which engages a complementary socket member 12^a on the side wall of the holder or trough 12. The opposite side wall of the holder or trough 12 has a trunnion 12^b which extends into a complementary socket 26^a formed in the respective axle 26, see Fig. 8.

A device has thus been created combining easy operation with improved dressing properties and permitting satisfactory adjustment of grinding stone in their operation.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A grinding wheel dresser comprising a trough having a flat bottom and shallow sides at right angles thereto, said trough being open at its front end, a grinding stone having a beveled front edge slidably mounted in said trough, said trough bottom having a longitudinal center slot, a clip having a right angle flange for engaging the top and rear edge of said stone, a portion extending rearwardly from said clip parallel to and spaced from said bottom, a rear vertical flange at right angles to said portion and engaging said trough bottom, said portion having a hole in line with said slot, a bolt passing through said slot and said hole whereby said clip and stone can be adjusted longitudinally of said trough to extend the beveled edge of said stone for engaging a grinding wheel, forwardly inclined depending legs attached at their upper ends to the side edges of

said trough bottom and extending to the front edge of said trough at a distance therebelow, a cross shaft journaled in the bottoms of said legs, an abrading wheel on said shaft including a row of alternate toothed and smooth discs for abrading the grinding wheel, and means engaging the sides of said trough adjacent its rear end for holding said trough in a pivoted position in which either said grinding stone or said abrading wheel engages the grinding wheel.

2. A grinding wheel dresser comprising a trough having a flat bottom and shallow sides at right angles thereto, said trough being open at its front end, a grinding stone having a beveled front edge slidably mounted in said trough, said trough bottom having a longitudinal center slot, a clip having a right angle flange for engaging the top and rear edge of said stone, a portion extending rearwardly from said clip parallel to and spaced from said bottom, a rear vertical flange at right angles to said portion and engaging said trough bottom, said portion having a hole in line with said slot, a bolt passing through said slot and said hole whereby said clip and stone can be adjusted longitudinally of said trough to extend the beveled edge of said stone for engaging a grinding wheel, forwardly inclined depending legs attached at their upper ends to the side edges of said trough bottom and extending to the front edge of said trough at a distance therebelow, a cross shaft journaled in the bottoms of said legs, an abrading wheel on said shaft including a row of alternate toothed and smooth discs for abrading the grinding wheel, and a pivotal mount engaging the shallow sides of said trough whereby either said grinding stone or said abrading wheel may be brought into operative position with relation to the grinding wheel.

3. A grinding wheel dresser comprising a trough having a flat bottom and shallow sides at right angles thereto, said trough being open at its front end, a grinding stone having a beveled front edge slidably mounted in said trough, said trough bottom having a longitudinal center slot, a clip having a right angle flange for engaging the top and rear edge of said stone, a portion extending rearwardly from said clip parallel to and spaced from said bottom, a rear vertical flange at right angles to said portion and engaging said trough bottom, said portion having a hole in line with said slot, a bolt passing through said slot and said hole whereby said clip and stone can be adjusted longitudinally of said trough to extend the beveled edge of said stone for engaging a grinding wheel, forwardly inclined depending legs attached at their upper ends to the side edges of said trough bottom and extending to the front edge of said trough at a distance therebelow, a cross shaft journaled in the bottoms of said legs, an abrading wheel on said shaft including a row of alternate toothed and smooth discs for abrading the grinding wheel, and a pivotal mount for said trough whereby either said grinding stone or said abrading wheel may be brought into operative position with relation to the grinding wheel, said mount including two transversely spaced posts, each having a top lug extending laterally toward said trough, one of said lugs having a circular socket and said trough side wall adjacent thereto having a trunnion in said socket, the other of said lugs having a circular chamber opening through the free end of said lug by means of a reduced opening, a flanged cylinder having a portion slidably retained in said chamber and having a trunnion at its outer edge, a socket member receiving said trunnion and mounted on the

other side wall of said trough in line with said trough trunnion, and a spring in said chamber urging said cylinder toward said trough.
